Primary Examiner — Mehri F Bajoul*(74) Attorney, Agent, or Firm* — Knobbe, Martens, Olson
& Bear LLP**CLAIM**The ornamental design for a video game controller, as shown
and described.**DESCRIPTION**FIG. 1 is a top perspective view of a video game controller
showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the video
game controller that form no part of the claimed design.**1 Claim, 5 Drawing Sheets**# US D1,085,236 S
